UNITED STATES PATENT OFFICE.

HARRY S. HART, OF CHICAGO, ILLINOIS.

CAR-TRUCK.

No. 865,493.

Specification of Letters Patent.

Patented Sept. 10, 1907.

Application filed December 17, 1906. Serial No. 348,269.

To all whom it may concern:

Be it known that I, HARRY S. HART, a citizen of the United States, residing at Chicago, in the county of Cook and State of Illinois, have invented certain new and useful Improvements in Car-Trucks, of which the following is a specification.

The object of my invention is to provide a car truck in which the bolster may be attached to the side frame of the truck, by means that will permit the use of an integral side frame, or, if a non-integral side frame is used, will permit the removal of the bolster from the side frame without separating the parts of which the latter is formed.

My improved construction embodies means whereby the bolster may be separated from the side frames without disarranging any of the other parts of the truck.

In the accompanying drawings—Figure 1 is a side view of a truck constructed in accordance with my invention. Fig. 2 is an enlarged view of the central portion of the truck, partly shown in section. Fig. 3 is a plan view of the structure shown in Fig. 2, a part of the view being in section on the line 5 of Fig. 2.

As shown in Fig. 2 of the drawings, the upper part 25 of the inner faces of the columns *d* are recessed as shown at *s*. The continuity of the inner faces of the columns is maintained, however, by the removable members *o*, which are of a form and size to fit the recesses referred to. The members *o* are removably secured in place by means of the keys *n*. As clearly appears from Fig. 3 of the drawings, the keys *n* coat with keyways located in the rear walls of the members *o* and of the recess *s*. These keyways are continued upward through the upper arch bar of the side frame 35 in the form of openings *m*, which permit of the insertion and removal of the keys *n*.

The bolster *e* is constructed in the usual manner with projecting lips *j*. In assembling the parts the removable interlocking members *o* are placed in position on either side of the bolster in the spaces formed by the projecting lips *j*. The end of the bolster, together with the interlocking members *o*, is then inserted in the aperture in the side frame. The mem-

bers *o* are thus caused to enter the recesses *s* in the upper portions of the columns. When the bolster has 45 been adjusted to its proper position the keyways in the interlocking members *o* will register with the keyways in the rear walls of the recesses *s*. The parts being in this position the keys *n* are driven home through the apertures *m* in the upper arch bar of the 50 side frame. When the parts are assembled as described, the bolster *e* will be firmly secured in place in the usual manner and will be permitted to move in a vertical direction upon the springs *g*, the inner surface of the interlocking members *o* being continuous with the inner integral surface of the lower portions of the columns *d*.

While I have illustrated my invention in connection with a bolster of the usual type co-acting with an interlocking member secured to the side frame by 60 a single key, it will be readily understood that other specific forms of construction come within the spirit of my invention.

What I claim is:

1. A side frame for a car truck comprising columns removable interlocking members for the bolster, said interlocking members being secured to the columns by means of keys. 65

2. A side frame for a truck having an opening to receive the end of the bolster, the side faces of said opening being recessed, removable interlocking members engaging said recesses, and keys securing said interlocking members to the side frame. 70

3. A side frame for a truck comprising columns spaced apart to receive the end of a bolster, recesses in the inner faces of said columns at their upper ends, keyways in the walls of said recesses, removable members adapted to fit said recesses and provided with keyways, and keys adapted to coact with said keyways. 75

4. In a car, a bolster, a side frame, column-guides, removable members forming part of said column-guides, said removable members and the fixed parts of said column-guides being provided with key-ways, the top of said side frame being provided with perforations registering with said key-ways, and keys co-operating with said key-ways. 80

HARRY S. HART.
